UNITED STATES PATENT OFFICE.

CLARENCE H. HAPGOOD, OF TOLEDO, OHIO.

SAFETY RAZOR.

REISSUED

Application filed September 21, 1923. Serial No. 663,996.

This invention relates to safety razors and has for its primary object the provision of a handle and holding frame pivotally supporting the blade for honing and stropping operations and adapted to receive a detachable guard plate for supporting the blade during the shaving operation.

Another object of the invention is the arrangement of a resilient clamp for detachably securing the blades in correct position for honing, stropping and shaving, the clamp being mounted upon a pivoted carrier adapted to engage the surface of a hone or strop and guide the blade for efficient sharpening, the carrier holding the clamp at an angle rendering it possible to strop the blade upon a soft leather strop with the edge of the blade foremost against the strop the same as in honing.

A further object of the invention is the provision of a detachable guard member adapted to fit over the blade and be secured upon the holding frame in varying positions to control the angular relation of the blade to the handle.

Other objects and advantages will be apparent from the following description wherein reference is made to the accompanying drawings illustrating preferred embodiments of my invention, and wherein similar reference numerals designate similar parts throughout the several views.

In the drawings:

Fig. I is a front elevation of a safety razor constructed in accordance with my invention.

Fig. II is a side elevation thereof.

Fig. III is an end view thereof looking toward the blade end of the razor.

Fig. IV is a transverse sectional view taken substantially on the line IV—IV of Fig. I, with varying positions of the blade and guard member shown in dotted lines.

Fig. V is an end view of the detachable guard member.

Figs. VI and VII are detail sectional views taken substantially on the lines VI—VI and VII—VII of Fig. III.

Fig. VIII is a side elevation of the holder frame and associated parts with a modified form of guard member.

Fig. IX is a rear elevation of this guard member.

Fig. X is a side elevation thereof.

Fig. XI is a detail sectional view taken substantially on the line XI—XI of Fig. I.

Fig. XII is a front elevation of my im-

proved razor constructed for use with double edged blades of the Gillette type.

Fig. XIII is a central sectional view taken substantially on the line XIII—XIII of Fig. XII.

Fig. XIV is a detail sectional view taken substantially on the line XIV—XIV of Fig. XIII.

Fig. XV is an end view of my razor with provisions for adjusting the blade relatively to the guard plate.

Fig. XVI is a side elevation thereof.

Fig. XVII is an enlarged detail view showing in side elevation the guard teeth and blade adjusting means, and

Fig. XVIII is a detail sectional view taken substantially on the line XVIII—XVIII of Fig. XVII.

Referring now to the drawings, the numeral 5 designates a handle and 6 a holder frame detachably secured thereto, as by the threaded stem 7. The holder frame is substantially U-shaped and provided with threaded apertures 6^a adjacent the ends of its tines for the reception of fulcrum screws 8 (see Fig. VI), the inner extremities of the fulcrum screws being rounded and adapted to fit within the apertured ends of the blade carrier 9 to permit ready rotation of the carrier, as hereinafter described. Encircling the carrier 9 is a clamp 10 of resilient metal, the ends of which extend radially from the carrier 9 and are adapted to securely hold a razor blade 11 during the honing or stropping operations as well as during the shaving operation. To co-operate with blades that have notches adjacent their side edges, as do many of the single edged blades now in general use, I preferably form the clamping jaws 10^a of the clamp with inturned projecting portions adjacent their sides, (see Figs. III and VII) the projecting portions fitting within the notches of the blade and serving to position the blade within the clamp. This prevents accidental movement of the blade within the clamp, and renders it easy to recognize when the blade is correctly positioned. Upon the ends of the carrier 9 are provided rollers 12 (note Fig. VI) which serve the purpose of retaining the clamp 10 in correct position upon the carrier 9 and also serve to provide a broader tractive surface upon the strop or hone.

The diameter of the clamp and rollers 12 are so related to the blade carried in the clamp 10 that when they rest upon the sur-

face of a hone or strop the beveled edge of the blade is tangent to the periphery of the clamp and rollers. By virtue of this construction it is possible to move the blade over the surface of the hone or strop with its edge foremost without cutting the strop or hone, even though flexible strops be used.

This is the correct position for sharpening razor blades and has been heretofore used in honing, but never in stropping, owing to the difficulty of moving a razor blade edge foremost over a flexible strop without cutting into the surface of the strop. The beveled edges of razor blades are ordinarily slanted substantially equally from the sides of the blade, and with such blades the movement of the blade over the strop or hone can be made in either direction.

The operation of honing or stropping would accordingly be carried out by merely resting the carrier upon the surface of the hone or strop, which is preferably kept in a substantially horizontal position, and the holder frame alternately pushed and pulled by pressure on the handle 5. The first movement of the carrier upon the surface of the hone or strop serves to turn the clamp and blade to bring the beveled edge of the blade into frictional contact with the hone or strop. This position is then maintained during the remainder of the stroke in one direction, the friction of the carrier against the strop or hone serving to maintain the edge of the blade in close contact with the surface. As soon as the handle is moved in the opposite direction the friction on the periphery of the carrier serves to rotate the clamp and blade until the opposite side of the beveled edge of the blade is in frictional contact with the strop or hone, whereupon further movement in that direction may be made with the beveled edge in engagement with the surface. These alternate movements over the strop or hone can be continued as long as desired.

The blade can now be used for shaving, without detaching it from the clamp 10, by the positioning of a guard plate 13 substantially as shown in Figs. I to V. The guard plate 13 as therein illustrated comprises a guard member 14 having rounded and downturned teeth 15 adjacent one end and a securing member of resilient material adapted to snap into position against the clamp and the inner face of the holder frame 6. The guard member 14 and securing member 13 are preferably welded or otherwise suitably united so as to form a substantially integral piece. The angle at which the blade 11 is held relatively to the handle 5 may be adjusted to suit the convenience by virtue of a plurality of aligned apertures 17 in the securing member 13, the central apertures being adapted to fit over the threaded stem 7 of the handle 5 and the side aper-

tures being adapted to fit over studs 16 extending from the inner surface of the holder frame 6, substantially as shown in Fig. I. The endmost guard teeth 15 are preferably bent upwardly and over the sides 70 of the blade to serve in positioning the blade upon the guard member and aid the projecting portions of the clamping jaws in preventing lateral movement of the blade within the clamp. The free extremity of the 75 securing member 13 is preferably curved to facilitate the positioning of the guard plate within the holder frame.

In Figs. VIII to XI inclusive is shown a slightly modified embodiment of the guard plate whereby the razor blade is positioned within the holder frame for shaving. This form of guard plate comprises substantially the same guard member 14 welded or otherwise secured to a metallic strip 130 curved 80 at its upper extremity to snugly fit over the clamp, and formed with apertured ears 131 for the reception of a pivot pin 132 upon which is pivotally connected a positioning strip 133 by apertured ears 134. A coil 85 spring 135 is mounted upon the pivot pin 132 with its ends engaging the strips 130 and 133 respectively to normally force them apart. The positioning strip 133 is provided with a plurality of spaced aligned 90 openings 136 for adjustment relatively to the holder frame 6. As illustrated in Fig. XI the adjusting openings 136 may be arranged adjacent each side of the strip 133 to co-operate with pins 137 on the holder frame, a central slot 138 being utilized to enable adjustment relatively to the threaded stem 7 whereby the handle 5 is secured to the holder frame.

In Figs. XII to XIV inclusive is shown an embodiment of the invention whereby double edged blades of the Gillette type may be employed. Substantially the same holder frame, guard member and carrier are employed as illustrated in Figs. I to VII 105 inclusive, but the clamp 100 is formed with one of its jaws 101 of greater length than the other jaw and provided with spaced raised portions 102 to fit within the apertures in the blade 103. The raised portions 110 102 correctly position the blade 103 within the clamp and are spaced a sufficient distance from the carrier 9 to prevent the edge of the blade within the clamp from contacting the carrier.

If desired, provision may be made for slightly moving the blade toward or away from the central teeth of the guard member. In Figs. XV to XVIII I have illustrated a preferred embodiment of such blade moving 115 means. The endmost guard teeth 15 are provided with downturned apertured ears 150 for the reception of the stub shafts 151 eccentrically mounted on the adjusting roller 152. This roller is preferably con-

structed with a plurality of faces spaced at different distances from the stub shafts 151, whereby, when the several faces are brought into contact with the lower surface of the 5 central guard teeth 15, the endmost teeth 15 are flexed relatively thereto, substantially as shown in Fig. XVII, the flexing of the endmost teeth serving to move the blade slightly on its pivotal mounting on the carrier. A knurled handle 153 is provided for ready rotation of the adjusting roller 152. The adjusting roller 152 is carried by the guard member 14 and may be removed with the guard member when it is desired to strop or hone the blade. After the desired adjustment of the blade relatively to the guard teeth is once secured, it may be held indefinitely, even though new blades be utilized with the guard member.

20 While it will be apparent that the illustrated embodiments of my invention herein disclosed are well calculated to adequately fulfill the objects and advantages primarily stated, it is to be understood that the invention is susceptible to variation, modification and change within the spirit and scope of the subjoined claims.

Having described my invention, I claim:

30 1. A safety razor having a holder frame, a blade carrier pivoted therein, a beveled edge blade adapted to be secured in the carrier with the beveled edge portion of the blade tangential to the periphery of the hub portion of the blade carrier, and a detachable guard plate arranged to engage the frame, the carrier, and the sides of the blade to secure the blade and carrier in predetermined angular relation to the holder frame.

40 2. A safety razor having a holder frame, a blade carrier pivoted therein, means for securing a blade in the carrier with the beveled edge portion of the blade tangent to the periphery of the blade carrier, and a detachable guard plate adapted to secure the 45 blade and carrier in predetermined angular relation to the holder frame, the guard plate being provided with a series of adjusting apertures for varying the angular relation of the blade and holder frame.

50 3. A safety razor having a holder frame, a blade carrier pivoted therein, a blade, and a detachable guard plate adapted to engage the edges of the blade, the carrier and the holder frame, the guard plate having a plurality of adjusting openings and a stud upon the holder frame adapted to fit within said openings.

60 4. A safety razor having a holder frame, a blade carrier pivoted therein, a blade, and a detachable guard plate adapted to engage the edges of the blade, the carrier and the holder frame, and means upon the blade carrier for correctly positioning the blade therein.

65 5. A safety razor having a holder frame,

a rotatable carrier pivoted therein, a blade securing clamp mounted over the carrier, a detachable blade, and means for securing the blade and carrier in predetermined angular relation to the holder frame comprising a 70 guard plate adapted to engage the blade, the clamp and holder frame, and means for adjustably securing the guard plate upon the holder frame.

6. A safety razor having a holder frame, a rotatable carrier pivoted therein, a blade securing clamp mounted upon the carrier, a detachable blade, and means for securing the blade and carrier in predetermined angular relation to the holder frame comprising a 75 guard plate adapted to engage the blade, the clamp and holder frame, and means to warp the guard plate for moving the blade relatively to the guard plate.

7. A safety razor having a holder frame, a rotatable carrier pivoted therein, a blade securing clamp mounted upon the carrier, a detachable blade, and means for securing the blade and carrier in predetermined angular relation to the holder frame comprising a 80 guard plate adapted to engage the blade, the clamp and holder frame, and means to warp the guard plate for moving the blade relatively to the guard plate.

8. A safety razor having a holder frame,

a rotatable carrier pivoted therein, a blade securing clamp mounted upon the carrier, a detachable blade, and means for securing the blade and carrier in predetermined angular relation to the holder frame comprising a 90 guard plate adapted to engage the blade, the clamp and holder frame, and means for warping the guard plate for adjusting the distance of the edge of the blade from portions of the guard plate.

9. A safety razor having a holder frame,

a handle adapted to be secured thereto, a carrier pivoted in the holder frame, a clamp mounted on the carrier, rollers secured on the carrier at each end of the clamp, a blade adapted to be secured in the clamp, and a detachable guard plate adapted to secure the blade in predetermined angular positions 100 relatively to the holder frame.

10. A safety razor having a holder frame,

a handle adapted to be secured thereto, a carrier pivoted in the holder frame, a clamp mounted on the carrier, rollers secured on the carrier at each end of the clamp, a blade adapted to be secured in the clamp, and a detachable guard member comprising a plate having teeth adapted to engage the edge of the blade and a securing member adapted to engage the holder frame.

11. A safety razor having a holder frame,

a handle adapted to be secured thereto, a carrier pivoted in the holder frame, a clamp mounted on the carrier, rollers secured on 120

- the carrier at each end of the clamp, a blade adapted to be secured in the clamp, and a detachable guard member comprising a plate having teeth adapted to engage the edge of the blade and a securing member adapted to engage the holder frame, and means carried by the guard member for adjusting the position of the cutting edge of the blade relatively to the guard teeth.
- 10 12. A safety razor having a holder frame, a handle adapted to be secured thereto, a carrier pivoted in the holder frame, a clamp mounted on the carrier, rollers secured on

the carrier at each end of the clamp, a blade adapted to be secured in the clamp, and a detachable guard member comprising a plate having teeth adapted to engage the edge of the blade and a securing member adapted to engage the holder frame, and a roller eccentrically mounted on the guard plate and adapted to move the blade toward or from the guard teeth.

In witness whereof I hereunto set my hand.

CLARENCE H. HAPGOOD.
